CLAIM

The ornamental design for laptop stand, as shown and described.

DESCRIPTION

FIG. 1 is a front perspective view of laptop stand, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the laptop stand in a folded state;

FIG. 10 is a rear perspective view thereof; and,

FIG. 11 is an enlarged detail view of area 11 in FIG. 1.

The broken lines in the drawings illustrate the portions of the laptop stand, which form no part of the claimed design.

(Continued)

The dash-dot-dash broken lines in FIGS. 1 and 11 show the boundaries of the enlargements shown in FIG. 11, and form no part of the claimed design.
